UNITED STATES PATENT OFFICE

VANCE S. FIRESTONE AND FRED SWARD, OF FREEPORT, ILLINOIS, ASSIGNEES TO
ARCADE MANUFACTURING COMPANY, OF FREEPORT, ILLINOIS, A CORPORATION OF
ILLINOIS

BRUSH HOLDER

Application filed October 8, 1931. Serial No. 533,764.

Our invention relates more particularly to devices for attaching brushes to handles, and our primary object is to provide a novel, simple and economical construction of this 5 character involving relatively few parts and which may be readily applied to, and detachable from, a brush, and readily adjustable to different sizes of brushes.

Referring to the accompanying drawing: 10 Figure 1 is a plan sectional view of a brush construction the handle and brush of which are connected together by holder means constructed in accordance with our invention, the section being taken at the irregular line 1—1 15 on Fig. 3 and viewed in the direction of the arrows.

Figure 2 is a view in front elevation of the construction of Fig. 1.

Figure 3 is a cross sectional view of the 20 construction of the preceding figures, the section being taken at the line 3 on Fig. 1 and viewed in the direction of the arrow; and

Figure 4, a section taken at the line 4 on Fig. 3 and viewed in the direction of the 25 arrow.

The particular illustrated construction of brush holder comprises a split socket member 5 adapted to receive and clamp thereto, the lower end of a brush handle 6 which, by 30 way of example, may be a bar or pole of such length as to permit the user, while standing substantially erect, to manipulate the brush across the floor.

The lower end of the member 5 terminates 35 in spaced apart plate portions 7 preferably rounded at their under surfaces at opposite ends thereof, as represented at 8 and 9, respectively.

The device also comprises a clamp jaw 10 40 in the form of a yoke the ends of its arms having inturned parts 11 which extend into openings in the plates 7, adapting the yoke 10 to swing on the member 5. The forward

cross bar portion 12 of the yoke 10 is deflected downwardly to adapt it to lap the front edge of the back of a brush to be clamped, as 45 for example the brush represented generally at 13 and the back of which is represented at 14.

The device also comprises a clamp jaw

15 for engaging the rear edge of the brush-back, this jaw being shown as in the form of a rod the rear end of which is bent downwardly as represented at 16 to engage the rear edge of the brush-back and the terminal end 55 of which is bent forwardly as represented at 17 to underlie the brush-back.

The jaw 15 is connected at its front end with the cross-piece 18 of a yoke 19 pivotally connected at its rearwardly extending arms 60 20, which extend into the space between the plates 7, with the front ends of these plates as by rivets represented at 21, the pivots 21 being located in front of, and, in the clamped position of the parts, above, the pivoting ends 65 11 of the arms of the yoke 10, as shown in Fig. 3.

In the use of the device, assuming the member 5 to extend at an angle to the vertical to the left in Fig. 3 in which position of the 70 parts the jaws 10 and 15 will be separated a sufficient distance to permit them to be applied to embracing position about the brush-back at the front and rear edges of the latter, the operator swings the member 5 by the handle portion 6, to the right in Fig. 3 to the position therein shown, the member 15 rocking 75 at the edges of its plate portions 7 against the top of the brush back and drawing the jaws 10 and 15 toward each other, 80 the pivoted connection of the yoke 19 with the plates 7 thereby becoming positioned above a line joining the pivots 11 and the portion of the yoke 10 at which it engages the front edge of the brush head, as shown in Fig. 3, 85 and thereby locking the holder clamp against accidental movement to brush releasing position. By preference, and especially where the brush-back to be clamped is of relatively

hard material, the jaws 12 and 15 are of a 90 material which is slightly springy to permit the movement of the parts of the holder to the position as above stated.

Provision is made for varying the distance 95 between the brush engaging parts of the jaws 10 and 15 to adapt the clamp holder to brushes having different widths of backs. In the particular construction shown the adjustment referred to is provided for by adjusting 100 by engaging the rod 15 with the yoke 19 as

by providing a screw thread 22 on the front end of the rod 15 which engages a similar thread in the opening in the cross bar 18 through which this rod extends.

5 While we have illustrated and described a particular construction embodying our invention, we do not wish to be understood as intending to limit it thereto as the same may be variously modified and altered without 10 departing from the spirit of our invention.

What we claim as new, and desire to secure by Letters Patent, is:

1. A brush holder comprising jaws adapted to clamp a brush therebetween, a handle 15 portion by which to manipulate the brush, said jaws separately pivoted to said handle portion to provide clamping action thereof by swinging movement of the handle, and means for relatively adjusting said jaws to 20 accommodate the holder to brushes of different sizes.

2. A brush holder comprising jaws adapted to clamp a brush therebetween, and a handle portion by which to manipulate the 25 brush, said jaws engaging said handle portion at different points thereon and in such position relative to each other that when said handle portion is swung in one direction said jaws will be relatively moved to clamp the 30 brush.

3. A brush holder comprising jaws adapted to clamp a brush therebetween, and a handle portion by which to manipulate the brush, said jaws being pivotally connected with said 35 handle portion at different points thereon and in such position relative to each other that when said handle portion is swung in one direction said jaws will be relatively moved to clamp the brush.

40 4. A brush holder comprising jaws adapted to clamp a brush therebetween, and a handle portion by which to manipulate the brush, said jaws being pivotally connected with said handle portion at different points thereon 45 and in such position relative to each other that when said handle portion is swung in one direction said jaws will be relatively moved to clamp the brush and the pivot of one of said jaws will extend above and between the line connecting the pivot of the other of said jaws with the point of engagement of said last-referred-to jaw with the brush.

5. A brush holder comprising jaws adapted 55 to clamp a brush therebetween, a handle portion by which to manipulate the brush, one of said jaws being in the form of a yoke pivoted to said handle portion, and the other of said jaws comprising a rod having a portion to engage the brush, a second yoke pivoted to said handle portion and engaged by said rod-jaw and extending in said first-named yoke, the pivoted connections of said yokes with said handle portion being at different points thereon.

6. A brush holder comprising jaws adapted to clamp a brush therebetween, a handle portion by which to manipulate the brush, and having a portion adapted to bear against the upper side of the brush, said jaws engaging said handle portion at different points thereon and in such position relative to each other that when said handle portion is swung in one direction said jaws will be relatively moved to clamp the brush and said handle portion will press against the upper side of the brush.

7. A brush holder comprising a handle portion presenting spaced apart plate portions at its lower end, jaws adapted to clamp a brush therebetween, one of said jaws being in the form of a yoke straddling said plates and pivoted to the latter, the other of said jaws presenting a rod portion, a second yoke located between said plates and pivoted thereto, said rod portion engaging said second yoke, said plates bearing against the upper surface of the brush and the pivot of said second yoke being located above and between a line connecting the pivot of said first-named yoke and the portion of the latter which clamps against the brush.
